UNITED STATES PATENT OFFICE

SIGURD KVALL, OF GRAND MEADOW, MINNESOTA, ASSIGNOR TO RED TOP STEEL POST COMPANY, OF CHICAGO, ILLINOIS, A CORPORATION OF ILLINOIS

POST PULLER

Application filed February 3, 1930. Serial No. 425,459.

This invention has reference to post pullers and it has for its principal object to provide a puller which is especially adapted for use in pulling or lifting metal fence posts of the plain and studded T type, also the angle type of post from the ground.

For some time now metal posts have been taking the place of the old type wood post, and of the metal posts which have become very popular because of their great utility and cheapness, as well as being easy to drive into the ground, are the plain and studded T post and the angle metal post. Such posts are especially adapted for supporting woven wire fencing and barb-wire and are used, not only for the permanent erection of field barriers, but also for temporary structures, and while in the development and use of such posts, efficient driving means have been devised, I am not aware that an efficient and cheap puller has been made, which would be especially useful for the pulling or lifting of such posts from the ground.

My invention comprehends a device which includes a bar, preferably a tubular bar, the acting end of which is slotted to receive the shank or leg portion of a T post and to provide a seat for the ridge or apical edge of an angle bar; the terminal of the slotted end of the bar being preferably rounded or beveled that it may ride against either type of post in a friction gripping relation; and said device further includes a link or strap of preferably U formation with its shank portions straddling the bar, on opposite sides of the slot and pivoted thereto to have free movement across the end of the bar. Said link or strap is adapted to be slipped down over a post and engaged under a stud of a studded type post and to frictionally engage against the edge portions of the angle sides of an angle post. When in such position, a block or equivalent means is placed under the acting end of the puller, whereby when pressure is applied to depress the outer end of the bar a leverage may be exerted to permit the grip between the end of the bar against the post and the link under a stud or against the edges of the angles of an angle bar, to lift or pull the post upward and out of the ground.

That the invention may be more fully understood, reference is had to the accompanying drawings, forming part of this description, illustrating a preferred embodiment of the invention, in which:

Fig. 1 is an elevation showing my improved puller applied for lifting a studded T type post from the ground, the bar of the puller being broken in its length;

Fig. 2 is a view in plan, as the same would appear on the line 2—2, Fig. 1, and

Fig. 3 is a view similar to Fig. 2, except that the puller is applied to an angle post.

Like characters of reference denote corresponding parts throughout the figures.

In the drawings a well known type of studded T post is designated A, having the studs a, see Figs. 1 and 2, and B designates the angle type of post, see Fig. 3.

The puller, comprising the invention, includes the bar 1, which is preferably a tubular bar, although not necessarily so. The acting end of this bar is slotted at 2 for a suitable distance, which slot as explained, is adapted to have the shank or leg portion of a T post inserted therein, see Figs. 1 and 2, when the device is applied to a T post for a pulling or lifting operation and the slotted end of the puller is rounded or beveled at 3, more especially useful for a friction gripping action against the inside face of the flanged side of the T post, see Fig. 1.

Having a pivoted connection with the slotted end of the puller, and at a suitable point beyond the inner end of the slot 2, is a link or strap 4, of preferably U formation, with the legs of such link or strap secured by a common pivot pin or bolt 5, and with the legs of the link preferably located on opposite sides of the slot 2. The cross-bar or connecting end of the link or strap may move across the rounded or beveled end of the bar 1 leaving sufficient space therebetween to enable the link or strap to be slipped down over a post, as shown in the figures. By beveling the inside face of the cross-bar or connecting end of the link or strap 4, as at 6, when a leverage movement is exerted on the bar 1, it insures the link or strap being positioned between studs on a post, see Fig. 1, while at

the same time, if the device is applied to an angle post a friction gripping relation may be maintained between the link or strap and the edges of the angle sides of an angle post.

- 5 In Fig. 1, I have shown a block C, or equivalent means, placed under the slotted end of the bar in close proximity to the post with which the device is applied as it is preferable to use it, near the ground, which, when pressure is applied to the outer end of the bar to depress it, gives the desired leverage for lifting the post out of the ground.
- 10

The device is disclosed in its simplest form, with the fewest number of parts and so constructed is cheap and yet very efficient, and while the disclosure is the preferred form, I do not wish to be limited thereto further than is expressed in the appended claim.

What I claim is:

- 20 A post puller applicable to studded T-posts, angle iron posts and the like comprising a leverage bar slotted for a portion of its length at one end for the insertion of the shank portion of a T-post and to provide a seat for the ridge portion of an angle post, and a U-shaped link having a pivotal connection at its ends with the slotted end of the bar and on opposite sides thereof beyond the base of the slot and disposed with relation to the 25 end of the bar for the placement of a post within said link and between the link and end of the bar and adapted to coact with the bar when a leverage action is applied thereto to lift the post.
- 30

35 In witness whereof, I have hereunto affixed my hand this 28th day of January, 1930.

SIGURD KVALL.
